CHARLES F. FREDE, OF ST. LOUIS, MISSOURI, ASSIGNOR TO COMMONWEALTH STEEL COMPANY, OF ST. LOUIS, MISSOURI, A CORPORATION OF NEW JERSEY.

RAILWAY-CAR UNDERFRAME

1,091,324.

Specification of Letters Patent. Patented Mar. 24, 1914.

Application filed March 31, 1913. Serial No. 758,083.

To all whom it may concern:

Be it known that I, CHARLES F. FREDE, a citizen of the United States, residing at the city of St. Louis, State of Missouri, have invented a certain new and useful Improvement 5 in Railway-Car Underframes, of which the following is a full, clear, and exact description, such as will enable others skilled in the art to which it appertains to 10 make and use the same, reference being had to the accompanying drawings, forming part of this specification, in which—

Figure 1 is a plan view of a body bolster forming a portion of a car underframe of 15 my improved construction. Fig. 2 is a side elevational view of the bolster seen in Fig. 1, and showing the center sills and side sills of the underframe in section. Fig. 3 is a vertical sectional view taken approximately 20 on the line 3—3 of Fig. 2. Fig. 4 is a cross sectional view taken approximately on the line 4—4 of Fig. 3.

This invention relates generally to railway car underframes, and more particularly 25 to the construction of the body bolster and the end portion of the center sill.

The principal object of my invention is to slot the end portion of the center sill or sills and to form an opening or openings through 30 the central portion of the body bolster in order that the end portion of the center sill can be combined with the body bolster so that said center sill projects a substantial 35 distance beyond the body bolster, thereby forming an interlocking connection which can be easily assembled, or in the case of repairs can be easily taken apart. By slotting the end portion of the center sill, it is possible to locate the bolster a short distance in 40 from the end of said center sill, and the projecting portion of the center sill serves as a point of attachment for draft sills which extend to the end sill of the underframe, and which draft sills are practically continuations of the center sills.

To the above purposes, my invention consists in certain novel features of construction and arrangement of parts hereinafter more fully described and claimed.

50 In the construction of the underframe as shown, I employ a pair of center sills, each comprising a vertically disposed web plate 10, to the upper and lower edges of which are fixed angles 11, the same being arranged

so that their horizontal flanges are outwardly presented. Positioned on top of the center sills thus formed is a cover plate 12, the edges of which are attached to the horizontal flanges of the upper pair of angles 11 by means of rivets. 55

The web plate 10 of the center sills are provided in their end portions with longitudinally disposed slots 13, which slots are for the accommodation of the top flange of the body bolster forming a part of the underframe. This body bolster is preferably 60 cast in a single piece and comprises a vertically disposed web 14, a top flange 15, and a bottom flange 16, and thus said bolster is substantially of I-beam shape in cross section. The vertically disposed webs 14 of the bolster are sometimes designated "intermittent diaphragms" which are provided with openings for the passage of train pipes, etc. 65

The central portion of the body bolster is preferably depressed with respect to its ends and the central portion of the top flange 15 occupies the inner ends of the slots 13. The length of these slots is approximately twice 70 the width of the top flange 13, so that when the body bolster is properly assembled with the center sills, the ends of the latter project a short distance beyond the body bolster. Openings 17 are formed through the web 14 75 of the bolster at points on opposite sides of the center thereof, which openings accommodate the lower portions of the web plates 10 and the lower pair of angles 11. 80

Formed integral with the web 14 and arranged at right angles thereto immediate adjacent the inner edges of the openings 17 are web plates 18, which lie immediately against the inner faces of the web plates 10, and these parts are rigidly fixed to each other 85 by means of rivets 19^a or like fastening devices.

Formed through the center of the body bolster is the usual vertically disposed opening 20 for the accommodation of the center 90 pin and formed integral with the underside of the bottom flange 16 between the openings 17 is a center bearing 19.

Formed integral with the underside of the bottom flange 16 to the sides of the center bearing, and beneath the openings 17 are short reinforcing ribs 20^a, which are for the purpose of strengthening that portion of the 100 105

bottom web 16 immediately beneath said openings.

Formed integral with the web 14 and to the sides of the openings 17 are vertically disposed strengthening ribs 21. The ends of the body bolster are provided with horizontally disposed plates 22 which receive the side sills 23 of the underframe and formed integral with the ends of the bolster 10 below these plates 22 are perforated plates 24 which are adapted to receive hooks on the ends of chains or cables utilized for pulling cars about while the same are in the yards or upon side tracks.

15 Formed integral with the bolster near its ends and on both sides thereof are outwardly projecting horizontally disposed flanges 25 which are adapted to receive nailing strips, and formed integral with the bottom flange 20 16 adjacent to these flanges 25 are side bearing plates 26.

In assembling the parts of the underframe, the bolster is positioned on the center sills with the central portion of the top flange 15 positioned in the inner ends of the slots 13, and the portions of the center sills beneath the slots 13 project through the openings 17. Rectangular filler plates 27 are now applied to the outer faces of the 30 web plates 10 between the edges of the vertically disposed flanges of the angles 11, which filler plates extend from the front edge of the top flange 15 to the ends of the web plates 10. Positioned directly against 35 these filler plates and against the end portions of the vertically disposed flanges of the angles 11 are the inner end portions of draft sills 28 preferably channel-shaped in cross section, and said draft sills are directly 40 connected to the center sills by means of rivets or like fastening devices, the same passing through the filler plates and the vertically disposed webs of the angles 11. The outer ends of the draft sills 28 are 45 attached in any suitable manner to the end sill 29 of the underframe. By depressing the central portion of the body bolster the tops of the side sills 23 fixed to the ends of said bolster occupy substantially the same 50 horizontal plane with the top plate 12 that is attached to the center sills. By slotting the center sills to accommodate a portion of the body bolster and attaching the inner ends of the draft sills to the ends of the center 55 sills, which project beyond the body bolster a very simple, strong and rigid construction is produced and the parts entering into such construction can be easily assembled or, in the case of repairs it will be a com- 60 paratively easy matter to remove the draft sills, thereby permitting the body bolster to be easily and quickly removed from the center sills.

It will be readily understood that minor 65 changes in the size, form and construction

of the various parts of my improved under-frame, can be made and substituted for those herein shown and described, without departing from the spirit of my invention, the scope of which is set forth in the appended 70 claims.

I claim:

1. In a car underframe the combination with center sills provided in their ends with slots, of a body bolster attached to said center sills, a portion of which body bolster occupies said slots so that parts of said center sills project entirely through and a substantial distance beyond said bolster. 75

2. In a car underframe, the combination with center sills provided in their ends with slots, of a body bolster connected to said center sills, so that the latter project entirely through and extend a substantial distance beyond the bolster, said body bolster having 80 a top flange which occupies the slots in the center sills. 85

3. In a car underframe, the combination with center sills provided in their ends with slots, of a body bolster having openings, a portion of which body bolster occupies the slots in the center sills, and parts of which center sills project entirely through and beyond the openings in the body bolster. 90

4. In a car underframe, the combination with center sills provided in their ends with slots, of a body bolster having openings to accommodate the parts of the center sills below the slots therein and which center sills project entirely through and extend a substantial distance beyond said bolster. 95 100

5. In a car underframe, the combination with center sills, of a body bolster having openings through and beyond which project parts of the center sills, and draft sills 105 rigidly fixed to the projecting portions of the center sills.

6. In a car underframe, the combination with center sills, of a body bolster, which sills are slotted to receive part of the body 110 bolster, the end portions of which sills project entirely through and beyond the body bolster and draft sills fixed to the extended ends of the center sills.

7. In a car underframe, the combination with a center sill provided in its end with a longitudinally disposed slot, of a body bolster having an opening adapted to accommodate a portion of the center sill, and a part of which body bolster occupies the slot in the center sill so that the slotted end of the center sill projects entirely through and beyond said body bolster. 115 120

8. In a car underframe, the combination with a center sill provided in its end with a longitudinally disposed slot, of a body bolster having an opening adapted to accommodate a portion of the center sill, a part of which body bolster occupies the slot in the center sill, so that the slotted end of 125 130

- the center sill projects entirely through and beyond said body bolster, and a draft sill fixed to the projecting end of the center sill.
9. In a car underframe, a center sill having a vertically disposed web provided in its end with a slot adapted to receive a portion of a body bolster which slot is greater in length than the width of the bolster so that the end of the center sill projects entirely through and beyond said bolster.
10. In a car underframe, a pair of connected center sills, having vertically disposed webs in which are formed slots adapted to receive parts of a body bolster which slots are greater in length than the width of the bolster so that the ends of the center sills project entirely through and a substantial distance beyond said body bolster.
11. In a car underframe, a body bolster provided near its center with openings adapted to receive parts of slotted center sills which latter project entirely through and a substantial distance beyond said body bolster.
12. In a car underframe, the combination with center sills, of a body bolster, parts of which pass through openings formed in the center sills, and parts of which center sills project entirely through openings in the body bolster.
13. In a car underframe, the combination with center sills, of a body bolster, parts of which pass through openings formed in the center sills, parts of which center sills project entirely through openings in the body bolster, and draft sills attached to the projecting portions of the center sills.
14. In a car underframe, the combination with center sills, of a body bolster, parts of which pass through openings formed in the center sills, parts of which center sills project entirely through openings in the body bolster, and means whereby said body bolster and center sills are rigidly fixed to each other.
15. In a car underframe, the combination with center sills, of a body bolster, which sills are slotted to receive parts of a body bolster, the slotted ends of which sills project entirely through and beyond the bolster, draft sills fixed to the projecting ends of the center sills, and means between the draft sills and the center sills for closing the slots thereof in front of the bolster.
16. In a car underframe, the combination with a center sill provided in its end with a longitudinally disposed slot, of a body bolster, having an opening adapted to accommodate a portion of the slotted end of the center sill, a part of which body bolster occupies the slot in the center sill, said slot being greater in length than the width of the body bolster so that the end of the center sill projects entirely through said bolster, and a draft sill fixed to the projecting end of the center sill for closing that portion of the slot in front of the bolster.
17. In a car underframe, the combination with a slotted center sill, of a body bolster provided with an opening, which sill and bolster are combined so that a portion of the body bolster occupies the inner portion of the slot in the center sill, a part of which center sill projects entirely through said bolster and means fixed to the projecting ends of the center sill for closing that portion of the slot between said projecting portions.
18. In combination, a pair of spaced center sills and a pair of spaced draft sills connected therewith to form extensions thereof, one pair of said sills being provided with longitudinally extending slots, and the other pair of said sills being arranged to cover one end of said slots, in combination with a bolster brought into assembled relation to said sills by movement longitudinally of the sills.
19. In combination a pair of spaced center sills having vertical web plates and a pair of spaced draft sills having vertical web plates, the plates of one pair of said sills being slotted and the other of said pair of sills being connected with the webs of the slotted sills at two sides of said slots, in combination with a bolster having a continuous portion spanning and projecting beyond said sills and another portion interposed between a pair of said sills.
20. In combination, a pair of spaced center sills and a pair of spaced draft sills connected therewith and forming continuations thereof, one pair of said sills being slotted and the other of said sills lapping the slotted sills at two sides of said slots, in combination with a bolster having a continuous portion spanning said sills and projecting through and beyond the same, and having another portion interposed between said sills.
21. In a car underframe, spaced center sills the webs of which are longitudinally slotted, a bolster having continuous top portions projected into said slot, spaced draft sills connected with the webs of said center sills above and below said slots and thereby closing the outer ends of the slots, and a portion of said bolster serving as a compression member between said center sills.
22. In combination, spaced flanged center sills and spaced flanged draft sills, the center sills having webs slotted to their ends and the draft sills being connected to said webs to form closures for parts of said slots, in combination with a bolster having a continuous portion extending through said slots and being seated therein by movement longitudinally of the sills, and having a portion disposed between said sills.
23. In combination, spaced channel shaped center sills slotted longitudinally from their

4
ends, a bolster having a continuous top portion and intermittent flanged diaphragms co-operating with said sills, the top portion occupying the slots of the sills and the diaphragms extending away from the sills, said bolster comprising a central portion connecting the diaphragms with the sills.

24. In combination, spaced channel shaped center sills slotted longitudinally from their ends, a bolster having a continuous top portion and intermittent flanged diaphragms co-operating with said sills, the top portion occupying the slots of the sills and the diaphragms extending away from the sills, said bolster comprising a central portion serving as the sole means for connecting the diaphragms with the sills.

25. In combination, spaced channel shaped center sills slotted longitudinally from their ends, a bolster having a continuous top portion and intermittent flanged diaphragms co-operating with said sills, the top portion occupying the slots of the sills and the dia-

phragms extending away from the sills, said bolster comprising a central portion connecting the diaphragms with the sills, and draft sills lapping the slotted portion of the center sills.

26. In combination, channel shaped center sills slotted longitudinally from their ends, a bolster comprising a single continuous recessed casting and a filler for said recess and having a continuous top portion and intermittent flanged diaphragms co-operating with said sills, the top portion occupying the slots of the sills and the diaphragms extending away from the sills, said bolster filler portion connecting the diaphragms with the sills.

In testimony whereof I hereunto affix my 40
signature in the presence of two witnesses,
this 14th day of March, 1913.

CHARLES F. FREDE.
